GAS LIGHT LAMP POST
Thomas Hart, 814 W. 5th St. S., Newton, Iowa
Filed Mar. 14, 1963, Ser. No. 265,140
5 Claims. (Cl. 240—82)

This invention relates to gas light lamp posts and particularly to the unit connecting the standard to the lantern.

Heretofore, there has been a problem of not being able to position sufficient gas feeder tubing in the coupling unit between the standard and the lantern to permit their separation. The coupling unit had to be designed small to avoid destroying the ornamental composition of the lamp post.

Therefore, it is an object of this invention to provide a gas light lamp post wherein the lantern may easily be removed from the standard.

It is a further object of this invention to provide a gas light lamp post having a coupling unit between the standard and the lantern that will permit storing of a length of gas feeder tubing that may be extended beyond the normal length of the coupling unit when the lantern is removed from the standard.

It is a further object of this invention to provide a gas light lamp post wherein the gas feeder tubing is coiled within the unit coupling the standard to the lantern and may be extended beyond the length of the coupling unit when the lantern is removed from the standard.

It is a further object of this invention to provide a gas light lamp post having a unit coupling the standard to the lantern which is particularly suitable for use with a standard comprising a plurality of solid legs.

It is a further object of this invention to provide a storage unit for a length of tubing whereby the tubing may be extended beyond the length of the storage unit.

It is still a further object of this invention to provide a gas light lamp post economical to manufacture, durable in use and refined in appearance.

These objects, and other features and advantages of this invention will become readily apparent upon reference to the following description when taken in conjunction with the accompanying drawings, wherein:

FIG. 1 is a side elevation view of the assembled gas light lamp post;

FIG. 2 is a cross-sectional view taken along line 2—2 in FIG. 1 of the unit used in coupling the standard to the lantern and showing the gas feeder tubing coiled and compressed in the limited space in the coupling unit; and

FIG. 3 is a cross-sectional view of the coupling unit of FIG. 2 disassembled and showing the gas feeder tubing coiled and extended.

The gas light post of this invention comprises generally as shown in FIG. 1, a standard 10 and a lantern 12 coupled by a unit 14.

The standard 10 comprises three solid leg members 16 uniformly spaced around a pipe member 18. Extending the length of the pipe member 18 is a gas feeder tube 20 (FIGS. 2 and 3). The lower ends of the leg members 16 and the pipe member 18 may be planted in the ground to any desired depth, usually not lower than the transverse brace elements 22 extending adjacent the ground between the pipe member 18 and each of the leg members 16.

In order to maintain the symmetry and composition of the standard 10 reflected in the leg structure 16, the pipe 18 used should have a diameter no larger than reasonably necessary to accommodate the tubing 20. The upper end of the pipe member 18 (FIGS. 2 and 3) is secured to the unit 14 in any suitable manner.

Referring now to FIG. 2, it is seen that the unit 14 comprises a pair of telescoping cylindrical sections 24 and

2

26 which are secured against relative movement by a pair of screws 27 provided in their mating walls on opposite side thereof. The shorter section 24 of the two is secured to the bottom side of the flat lantern base 28. The other section 26 extends inside section 24 and abuts at one end against the bottom side of the flat lantern base 28. Formed in the center of the other end 30 of the section 26 is a small hole to receive the tubing 20 from the pipe 18. As illustrated in FIG. 2, the tubing 20 has coils 31 formed therein and compressed with the upper end provided with a coupling element 32 adapted to be threadedly engaged by the coupling element 34 mounted in the base 28 of the lantern 12.

In FIG. 3, the sections 24 and 26 of the coupling unit 14 are separated along their longitudinal axis, thereby causing the tubing 20 to expand like a coil spring. It is noted that sufficient coils 31 of tubing 20 should be provided to avoid kinking the coil when it is extended.

In assembling the gas light lamp post it is apparent then that one procedure that may be followed is to secure section 26 to the upper ends of the legs 16 and the pipe member 18; then forming a plurality of coils 31 at one end in a length of tubing 20, and extending the other end through the section 26 and the pipe 18 whereupon it is connected to a gas supply.

The coupling element 32 on the coiled end of the tubing 20 is connected to a mating coupling element 31 mounted in the base 28 of the lantern 12, but to make this connection, the tubing 20 must be extended beyond the upper end of section 26 to provide access to the coupling elements 32 and 34. The extension of the tubing is accomplished by the coils 31 expanding relative to each other as in a coil spring (FIG. 3). Next, the section 24 is moved toward section 26 into embracing relationship therewith (FIG. 2) until the upper end of casing 26 abuts the lantern base 28. The coils 31 of tubing are then in their retracted position as seen in FIG. 2. The sections 24 and 26 are then secured against relative movement by screws 27 being inserted through the walls thereof.

With the gas supply turned on, the lantern may then be lit to provide a flame 35 (FIG. 2).

When repairs to the lamp post are required, disassembly of the unit 14 is easily accomplished by removing screws 27 and pulling apart sections 24 and 26, thereby expanding the extendable coil 31. Any point in the unit may then be easily reached due to the accessibility afforded by extendable coil tubing 31.

Some changes may be made in the construction and arrangement of my gas light lamp post without departing from the real spirit and purpose of my invention, and it is my intention to cover by my claims, any modified forms of structure or use of mechanical equivalents which may be reasonably included within their scope.

I claim:

- 55 1. In a gas lamp post,
a standard;
a cylindrical unit mounted on top of said standard and
comprising two telescoping sections;
a gas light lantern having a base secured to the top of
one of said sections, the other section being secured
to said standard;
and a metallic tube for supplying gas to said lantern
extending longitudinally through said unit and cou-
pled to the base of said lantern, said tube being coiled
within said unit and adapted to be expanded longi-
tudinally to permit relative longitudinal separation of
said telescoping sections, thereby providing access to
the interior of said telescoping sections.

a cylindrical unit comprising first and second telescoping cylindrical sections, said first cylindrical sections being open at one end and the other end being secured to said standard, said secured cylindrical section being open at one end and the other end being secured to the base of said lantern, said first and second cylindrical sections having their open ends telescoped together;

and a length of metallic tubing extending through said other end of said first cylindrical section, said length of tubing being coiled within said cylindrical unit and secured to the base of said lantern, said coil adapted to expand longitudinally to a length greater than the combined length of said first and second sections of said unit upon relative longitudinal separation of said first and second cylindrical sections, thereby providing access to the interior of said telescoping sections while said tube remains coupled to said lantern base.

3. In a gas lamp post,

a standard;

a lantern having a flat base;

a cylindrical hollow, elongated unit adapted to connect said lantern to said standard, said unit comprising first and second sections adapted to be telescopically engaged, one of said sections having a small hole formed in one end and the other end being open, said first end being secured to said standard, and the other end being adapted to engage the base of said lantern, said second section being adapted to telescopically engage said first section and having one end secured to said base of said lantern;

and a length of metallic tubing extending through said small hole, said length of tubing being coiled within said cylindrical hollow elongated unit with one end of said tube connected to said base of said lantern, said length of tubing adapted to be expanded to a greater length than the combined lengths of said first and second sections of said unit upon said first and second sections being longitudinally separated, thereby providing access to the interior of said telescoping sections while said one end of said tube remains coupled to said lantern base.

4. In a gas lamp post,

a standard;

a lantern having a flat base with a coupling element mounted therein;

a cylindrical hollow, elongated unit adapted to connect said lantern to said standard, said unit comprising first and second sections adapted to be telescopically engaged, one of said sections having a small hole formed in one end and the other end being open, said first end being secured to said standard, and the other end being adapted to engage the base of said lantern, said second section being adapted to telescopically engage said first section and having one end secured to said base of said lantern;

and a length of metallic tubing extending through said small hole, said length of tubing being coiled within said cylindrical hollow elongated unit and terminating in a detachable coupling element connected to said coupling element in said base of said lantern, said length of tubing adapted to be expanded to a greater length than the combined length of said first and second sections of said unit upon said first and second sections being longitudinally separated, thereby providing access to the interior of said telescoping sections while said tube remains coupled to said lantern base.

5. The structure of claim 4 wherein said first section telescopically embraces said second section and said second section has a length exceeding that of said first section.
